UNITED STATES PATENT OFFICE

KENNETH L. TATE, OF ROCHESTER, NEW YORK, ASSIGNOR TO TAYLOR INSTRUMENT COMPANIES, OF ROCHESTER, NEW YORK, A CORPORATION OF NEW YORK

APPARATUS FOR MAKING CAPILLARY TUBES

Application filed March 19, 1929. Serial No. 348,344.

This invention relates to apparatus for making capillary tubes such as are used in connection with mechanical distance thermometers.

- 5 In the patent to Hodgkinson No. 1,063,349 is described a capillary containing a wire for reducing the capillary bore volume. In the application of D. D. Rosenburgh, Ser. No. 142,632, filed on Oct. 19, 1926, is described a 10 capillary wherein the surface of the capillary bore is substantially smooth and uniform and the clearance between the wire and the bore is reduced to a small fraction of the clearance involved in the Hodgkinson patent.
- 15 It is the object of the present invention to provide apparatus for forcing a wire into a capillary whose bore is smooth and uniform but of a diameter not more than about .0015" greater than the diameter of the wire.
- 20 For a full understanding of the invention, reference is made to the accompanying drawings, wherein

Fig. 1 is a more or less diagrammatic elevational view of apparatus embodying the 25 invention;

Fig. 2 is a sectional view taken on line 2—2, Fig. 1;

Fig. 3 is a section, on an enlarged scale of 30 part of the mechanism shown in Fig. 1; and

Fig. 4 is a section taken on line 4—4, Fig. 3.

Having reference to Fig. 1, 1 is a reel containing the wire 2 to be forced into the capillary 3. The latter is supported on a bench 4 in bearings adapted to hold it in a substantially straight line for rotation. In the particular arrangement disclosed, the bench, which may have any desired length, carries a plurality of brackets 5 spaced about 2-3 ft. apart, each bracket having a V-shaped configuration defining at the apex of the V a notch 5^a rounded at the bottom to support the capillary 3. Adjacent the brackets are arcuate arms 6 supported upon a rod 7 which extends substantially the whole length of the bench 4 and is mounted in bearings 8 and 9 for rotation by a handle 10. The arms may be swung to one side, as shown in dotted line in Fig. 2, so that the capillary may be entered in the notches 5^a and then the arms are 45 swung back over and across the brackets to

form locking bars preventing the capillary from moving upwardly. The brackets, being in alignment with each other, hold the capillary in a straight line.

To reduce friction, the arms 6 carry pieces 55 of leather 6^a or the like, projecting slightly below the lower edge of the arms to bear upon the capillaries.

Mechanism is provided for feeding the wire 2 from the reel 1 into the capillary 3 60 and for rotating the latter at the same time.

The end of the capillary 3 into which the wire is to be fed, is supported in a bearing 11 having a flaring mouth 11^a to facilitate the entering of the capillary. The inner end of 65 the mouth 11^a receives the capillary with just sufficient clearance to avoid undue friction during rotation of the capillary 3.

The bearing 11 has an extension 12 in axial alignment with the mouth 11^a, said extension 70 having an axial bore 13 concentric with and leading into the mouth 11^a. This arrangement makes it possible that the wire 2 may be passed into the capillary without any intervening gap.

The wire 2 is passed through a curved, preferably S-shaped tube 14 between two rolls 15 which are rotated by a motor 16 and suitable transmission mechanism including a reducing unit 17 and force the wire into 80 the capillary 3. The rolls 15 are provided with aligned grooves 18 of preferably semi-circular cross-section and are forced toward each other by spring pressure. In the particular arrangement, the rolls are mounted in a frame 19 on shafts 20. The shaft of the lower roll is journaled directly in the frame 19, while the shaft of the upper roll is journaled in a yoke 21 movably mounted in guideways 21^a in frame 19. The latter has 85 a turret-like part 22 bored to provide a housing for a piston element 23, a spring 24 and an abutment plate 25. This plate 25 may be adjusted by means of a screw 25^a or the like, to vary the pressure of the spring 24 90 upon the piston 23 and through it upon the upper roll 15.

For the rotation of the capillary, I have provided a chuck 26 mounted between the bearing 11 and the bench 4 and driven by a 100

motor 27. The chuck including the handle 28, the pulleys 29 and the mounting 30 may be of a usual or standard construction and does not, as such, form part of the invention.

5 The operation is as follows:

The wire 2 is initially passed by hand through the curved tube 14, the grooves 18 of the rolls 15 into the bore 13 of the extension 12 far enough to cause it to enter the capillary 3. Then the motor 27 and the motor 16 are started in succession.

10 The mechanism for turning the rolls is so designed and adjusted as to normally feed the wire at a speed of about 20 ft. per minute and 15 the mechanism for rotating the capillary 3 is so chosen as to normally impart to the capillary a speed of about 1200 R. P. M.

15 It is understood that the speeds referred to are by no means invariable, but merely represent what I have found to be a very satisfactory arrangement. The ratio of rotary speed to axial speed is very high and in the particular instance referred to equals 60 revolutions for 1' or 5 revolutions for 1" of axial 20 feed. The practical significance of this ratio is that the motion necessary to enter the wire has been split up into two components, an axial component and a lateral component defining in conjunction a sinusoidal path according to equation $y=a \sin x$. The resistance opposing the entering of the wire is therefore materially reduced. I have found that a wire having a diameter of .029" may be readily forced into a capillary having a bore 25 of .030" diameter, which would be impossible by linear movement alone.

30 The rolls 15 being continuously and uniformly driven, the feed is generally uniform but may, in case of emergency, adapt itself to 40 conditions and even stop without material damage to the wire. The tension of spring 24 may be so adjusted as to provide the normal gripping action necessary to overcome the resistance offered by the bore of the tube. 45 In case an unusual resistance is encountered such as could not be immediately overcome by the drilling action of the wire, the rolls will slip and the operator will soon discover it.

50 Since the wire is confined in a bearing extending close to the feed point of the rolls 15 and the extension 12 is in axial alignment with the plane of contact of the rolls, a considerable axial pressure may be exerted on the wire without danger of buckling even with wires of diameters of the order of .01". In other words, the axial thrust may be a maximum.

55 The curved tube 14 has the purpose to set up a large resistance against torsional motion of the wire which might be induced by the rotary movement of the capillary.

60 The grooves 18 are preferably semi-circular to avoid as much as possible distortion of the

surface of the wire and yet obtain an effective gripping action.

While I have described what I consider at present as the best and preferred embodiment of my invention, I want to have it understood that there is considerable latitude in various directions.

65 I claim:

1. Apparatus for entering a wire into a flexible tube, comprising means defining a plurality of aligned bearings constructed and arranged to maintain the flexible tube in a substantially straight line and free to be rotated, means for rotating the tube and means for continuously feeding the wire into the tube.

70 2. Apparatus for entering a wire into a flexible tube, comprising a bearing constructed and arranged to hold one end of the tube free to undergo rotary motion about a fixed axis of rotation, a plurality of bearings in axial alignment with said bearing, constructed and arranged to permit rotation of the tube and to maintain the tube during rotation in a straight line, means for rotating the tube and means for continuously feeding the wire into the said end of the tube.

75 3. Apparatus for entering a wire into a flexible tube, comprising a plurality of axially aligned bearings having lateral openings for receiving the tube in a direction at right angle to its direction of length, means for closing said openings and for maintaining the tube in a substantially straight line, a bearing for one end of the tube, constructed and arranged to receive the tube in axial direction and to maintain it in axial alignment with the other bearings, means for rotating the tube and means for continuously feeding the wire into the tube.

80 4. Apparatus for entering a wire into a flexible tube, comprising a bearing for one end of the tube permitting rotation of the same about a fixed axis, a support for the tube extending from the opposite end to near said bearing, for maintaining the tube in a substantially straight line, means between said bearing and said support for rotating the tube and means for feeding the wire into the tube at the end held in said bearing.

85 5. Apparatus for entering a wire into a capillary tube, comprising a member having two aligned concentric bores, a larger bore for receiving one end of the capillary tube and a smaller bore for conducting the wire into the bore of the said capillary tube, said smaller bore being substantially of the size of the bore of the capillary tube.

90 6. Apparatus for entering a wire into a capillary tube, comprising a member having two aligned concentric bores, a larger bore for receiving one end of the capillary tube and a smaller bore for conducting the wire into the bore of the capillary tube, the smaller bore being substantially of the size of the bore

of the capillary tube, means for feeding the wire into the said smaller bore and means for rotating the capillary tube about the axis of the larger bore.

- 5 7. Apparatus for entering a wire into a capillary tube, including a member having a bore for receiving one end of the capillary tube and holding the same for rotation about a fixed axis, the said member also having a 70
10 smaller bore in axial alignment with the larger bore for conducting the wire into the bore of the capillary tube, the smaller bore having substantially the size of the bore of the capillary tube and the outer ends of the 75
15 bores flaring outwardly to facilitate the entering of the capillary tube and the wire respectively.
8. Apparatus for entering a wire into a flexible tube, comprising means for revolubly 80
20 supporting the tube about a fixed axis including a bearing at one end, means intermediate the ends of the tube for rotating the same, means adjoining the said bearing for conducting the wire into the bore of the flexible tube 85
25 and means immediately adjacent the said conducting means for moving the wire in axial direction.
9. Apparatus for entering a wire into a flexible tube, comprising means for revolubly 90
30 supporting the tube about a fixed axis, means for rotating the tube, means for axially moving the wire and means between the moving means and the tube for holding the wire in axial alignment with the latter.
- 35 10. Apparatus for entering a wire into a flexible tube, comprising means for revolubly supporting the tube about a fixed axis, means for rotating the tube, means for axially moving the wire, means between the moving 95
40 means and the tube for holding the wire in axial alignment with the latter and means in advance of the moving means acting upon the wire to oppose rotary movement thereof. 100
105
11. Apparatus for entering a wire into a flexible tube, comprising means for revolubly 110
45 supporting the tube about a fixed axis, means for rotating the tube, means for axially moving the wire and means connected with the wire in advance of the tube, tending to oppose rotary movement of the wire.
12. Apparatus for entering a wire into a flexible tube, comprising means for revolubly 115
50 supporting the tube about a fixed axis, means for rotating the tube, resiliently yielding means for axially moving the wire and means in advance of the moving means, tending to oppose rotary movement.
13. Apparatus for entering a wire into a flexible tube, comprising means for revolubly 120
55 supporting the tube about a fixed axis, means for rotating the tube, means for conducting the wire into the tube and resiliently yielding means in advance of the conducting means for axially moving the wire.
- 60 14. Apparatus for entering a wire into a flexible tube, comprising means for revolubly 125
65 supporting the tube about a fixed axis, means for rotating the tube, means for conducting the wire into the tube, means acting upon the wire, tending to oppose rotary movement thereof, and resiliently yielding means for axially moving the wire into the tube. 70

105
110
115
120
125
130
15. The combination of a pair of rolls having aligned grooves, resilient means for pressing the rolls toward each other, a member having at one end a bore for receiving the end of a capillary tube and having in opposite direction in axial alignment with the bore an extension having a fine bore for conducting a wire into the said bore centrally thereof, and means for supporting said member to one side of the rolls in the plane of the grooves and substantially in the plane tangent to the points of contact between the rolls, with the end of the said extension in close proximity to the line of contact between the rolls. 80
16. The combination of a pair of rolls having aligned grooves, resilient means for pressing the rolls toward each other, a member having at one end a bore for receiving the end of a capillary tube and having in opposite direction in axial alignment with the bore an extension having a fine bore for conducting a wire into the said bore centrally thereof, and means for supporting said member to one side of the rolls in the plane of the grooves and substantially in the plane tangent to the line of contact between the rolls with the end of the said extension in close proximity to the line of contact between the rolls. 90
95
100
17. The combination of a pair of rolls having aligned grooves, resilient means for pressing the rolls toward each other, a member defining at one end a tubular portion for receiving the end of a capillary tube and defining at the opposite end a capillary tube having its bore in axial alignment with said tubular portion and means of supporting the said member with its axis disposed substantially in the plane of the grooves and the plane of the tangent through the point of contact between the rolls, the free end of the capillary tube portion of the said member terminating in close proximity to the line of contact between the rolls. 115
120
18. In apparatus for entering a wire into a capillary tube, the combination of means for rotating the tube about a fixed axis of rotation and means for continuously pushing the wire into the tube at a rate of approximately 1' for 60 revolutions of the tube. 125
19. In apparatus for entering a wire into a capillary tube, the combination of means for rotating the tube about a fixed axis of rotation, resiliently yielding means for continu-

ously pushing the wire into the tube and means near the pushing means tending to hold the wire against rotation.

20. In apparatus for entering a wire into a capillary tube, the combination of means for rotating the tube about a fixed axis of rotation, resiliently yielding means for pushing the wire into the tube, means between the pushing means and the tube for conducting the wire against lateral distortion and means near the pushing means tending to hold the wire against rotation.

In testimony whereof I affix my signature.
KENNETH L. TATE.
